UNITED STATES PATENT OFFICE

150,912

DESIGN FOR A COMBINED DRAWER PULL
AND LABEL HOLDER

Gilbert Stanley Underwood, Washington, D. C.

Application December 9, 1946, Serial No. 135,360

Term of patent 3½ years

(Cl. D10—8)

To all whom it may concern:

Be it known that I, Gilbert Stanley Underwood, a citizen of the United States, residing in Washington, District of Columbia, have invented a new, original, and ornamental Design for Combined Drawer Pull and Label Holders, of which the following is a specification, reference being had to the accompanying drawings, forming a part thereof.

In these drawings:

Figure 1 is a front elevation of a combined drawer pull and label holder.

Figure 2 is a section on the line 2—2 of Figure 1.

I claim:

The ornamental design for a combined drawer pull and label holder, as shown and described.

GILBERT STANLEY UNDERWOOD.
